UNITED STATES PATENT OFFICE.

RAYMOND S. DICKINSON, OF LOS ANGELES, CALIFORNIA.

ROTARY INTERNAL-COMBUSTION ENGINE.

1,034,213.

Specification of Letters Patent. Patented July 30, 1912.

Application filed September 8, 1911. Serial No. 648,299.

To all whom it may concern:

Be it known that I, RAYMOND S. DICKINSON, a citizen of the United States, residing at Los Angeles, in the county of Los Angeles and State of California, have invented certain new and useful Improvements in Rotary Internal-Combustion Engines, of which the following is a specification.

This invention relates to that class of rotary internal-combustion engines having a plurality of cylinders in which operate reciprocating pistons which are connected to a stationary crank shaft around which shaft the cylinders revolve.

It is the object of the present invention to provide in an engine of the kind stated a novel connection between the pistons and the crank shaft, together with an arrangement of ports and gas passages whereby a two-cycle engine is had.

In order that the invention may be better understood, reference is had to the accompanying drawing forming a part of this specification, in which drawing two sectional views of the engine are shown, Figure 1 being a longitudinal section on the line 1—1 of Fig. 2, and Fig. 2 a transverse section on the line 2—2 of Fig. 1.

Referring specifically to the drawing, 5 denotes the stationary crank shaft, the same being supported in any suitable manner, which is immaterial to the present invention. The shaft is provided with two coinciding cranks 6 to which the reciprocating pistons 7 working in the cylinders 8 are connected in a manner to be presently described. The cylinders are arranged radially and located diametrically opposite each other between the cranks, and they are connected at their inner ends to a hub 9 rotatably mounted on the shaft. The inner ends of the cylinders are in open communication with ports 10 in the hub, which ports successively register with a port 11 in the shaft, the last-mentioned port leading from an axial fuel passage 12 in the shaft, said passage being connected to any suitable source of fuel supply (not shown).

Two piston rods 13 are provided for each piston 7, said rods being located on the outside of the cylinders 8, on opposite sides thereof, and connected to the cranks 6. The connection between the piston and the rods is made by a wrist pin 14 passing trans-

versely through the body of the piston intermediate its ends, and through longitudinal slots 15 in the cylinder wall.

The engine is a two-cycle engine, the pistons acting as working pistons as well as pump pistons to supply a fresh charge. 60 The outer ends of the cylinders and the corresponding ends of the pistons constitute the working cylinders and the inner ends of the cylinders and the corresponding ends of the pistons form pumps. In the last-mentioned 65 end of each cylinder is a port 16 which is connected by a by-pass 17 to the inlet port 18 of the working end of the cylinder, and opposite the last-mentioned port is an exhaust port 19. The working end of the piston has a deflector 20, as usual, and a suitable igniter (not shown) is also provided, the operation thereof being timed by any suitable mechanism which has not been described and shown as it is well known to 75 those skilled in the art.

The shaft 5 is in two sections which are connected by a screw or other joint 21 intermediate the cranks 6. Two cylinders are shown, but it will be understood that their 80 number may be increased to suit the work for which the engine is designed.

In operation, the cylinders revolve around the crank shaft, and the ports 10 alternately come opposite the ports 11. This takes 85 place on the outward stroke of the piston, whereupon a charge is drawn into the inner or pump end of the cylinder. On the next or inward stroke of the piston, the port 10 having in the meantime been closed by passing the port 11, the charge in the inner end of the cylinder is partly compressed, and when the working end of the piston uncovers the port 18, said charge is admitted into the working end of the cylinder behind the piston, and compressed on the next outward stroke. The charge is then ignited, and the piston makes a working stroke, at the end of which the port 19 is uncovered by the working end of the piston, and the spent gases 90 are exhausted. In the meantime a fresh charge had been drawn into the pump end of the cylinder on the compression stroke, which charge is delivered into the working end of the cylinder at the end of the firing 100 stroke as before. The two cylinders are arranged so that the firing stroke occurs in alternate order.

I claim:

1. A rotary internal-combustion engine 110

- comprising a stationary crank shaft having an axial fuel passage and a port communicating with said passage and opening through one side of the shaft, a hub rotatably mounted on the shaft over the port, said hub having ports which are adapted to alternately register with the port of the shaft, longitudinally slotted radial cylinders mounted on the hub over the ports thereof, reciprocating pistons working in the cylinders, one end of said cylinders being working cylinders and having inlet and exhaust ports, and the other ends being pump cylinders, the ports of the hub opening into the last-mentioned ends of the cylinders, by-passes connecting the pump ends of the cylinders and the inlet ports of the working ends of the cylinders, wrist pins connected to the pistons and extending from opposite sides of the cylinders through the slots thereof, and rods connecting the ends of the wrist pins to the respective cranks of the shaft.
2. A rotary internal-combustion engine comprising a stationary shaft having a pair of coinciding cranks, and said shaft having an axial fuel passage and a port communicating with said fuel passage and opening through one side of the shaft between the cranks, a hub rotatably mounted between the cranks, said hub having ports which are adapted to alternately register with the port of the shaft, longitudinally slotted radial cylinders mounted on the hub over the ports thereof, reciprocating pistons working in the cylinders, one end of said cylinders be-
- ing working cylinders and having inlet and exhaust ports, and the other ends being pump cylinders, the ports of the hub opening into the last-mentioned ends of the cylinders, by-passes connecting the pump ends of the cylinders and the inlet ports of the working ends of the cylinders, wrist pins connected to the pistons and extending from opposite sides of the cylinders through the slots thereof, and rods connecting the ends of the wrist pins to the respective cranks of the shaft.
3. A rotary internal-combustion engine comprising a stationary crank-shaft having an axial fuel passage and a side port leading from said passage, a hub rotatably mounted on the shaft, said hub having ports which alternately register with the aforesaid side port, radial cylinders mounted on the hub, the inner ends of the respective cylinders being in constant communication with the ports of the hub, reciprocating pistons working in the cylinders, one end of said cylinders being working cylinders, and the other end being pump cylinders, by-passes connecting the respective ends of the cylinders, wrist pins connected to the pistons, and rods connected to said wrist pins and to the crank-shaft.

In testimony whereof I affix my signature in presence of two witnesses.

RAYMOND S. DICKINSON.
